No. 653,700.

Patented July 17, 1900.

J. ROSE.

HORSE DETACHER.

(Application filed Apr. 25, 1900.)

(No Model.)

FIG. 1.

UNITED STATES PATENT OFFICE.

JOHN ROSE, OF VOLNEY, IOWA.

HORSE-DETACHER.

SPECIFICATION forming part of Letters Patent No. 853,700, dated July 17, 1900.

Application filed April 25, 1900. Serial No. 14,362. (No model.)

To all whom it may concern:

Be it known that I, JOHN ROSE, a citizen of the United States, residing at Volney, in the county of Allamakee and State of Iowa, have 5 invented a new and useful Horse-Detacher, of which the following is a specification.

The invention relates to improvements in horse-detachers.

One object of the present invention is to 10 improve the construction of horse-detachers and to provide a simple, inexpensive, and efficient device adapted in the event of a runaway to enable a pole or a pair of thills to be readily detached from a vehicle to prevent 15 injury to the latter and its occupants.

A further object of the invention is to provide a device of this character which will also facilitate coupling and uncoupling and which will enable a pole to be readily changed for 20 a pair of thills, and vice versa.

The invention consists in the construction and novel combination and arrangement of parts hereinafter fully described, illustrated in the accompanying drawings, and pointed 25 out in the claim hereto appended.

In the drawings, Figure 1 is a plan view of a horse-detacher constructed in accordance with this invention and shown applied to an axle. Fig. 2 is an elevation of the same, 30 partly in section, the locking-rods being in engagement with the eyes of the coupling-irons. Fig. 3 is an elevation, the locking-rods being withdrawn.

Like numerals of reference designate corresponding parts in all the figures of the drawings.

1 and 2 designate a pair of reciprocating locking-rods located at the front face of a front axle 3 and having their outer ends arranged to extend through the perforated ears 4 of axle-clips 5 to form pivots for connecting the coupling-irons 6 of a pole 7 to the front axle; but instead of pivoting the pole 7 to the front axle a pair of thills may be coupled 40 to the said axle, as will be readily apparent. The rods 1 and 2, which have their outer ends extending through the perforated ears, are supported at points between their ends at opposite sides of the center of the axle by a pair 45 of guides 8, consisting of upwardly-extending arms of clip-plates 9 of clips 10. The clips 10, which are constructed substantially the

same as the axle-clips 5, with the exception of the perforated ears, embrace the axle, and the said clip-plates 9 are extended forward 55 and bent upward to form the guide-arms and are perforated for the reception of the rods. The guides support the inner portions of the rods 1 and 2, which are reciprocated longitudinally by an operating-lever 11. The 60 rod 1, which is located at the right-hand side of the vehicle, has its inner end 12 bent upward to form an approximately L-shaped arm, and the other rod 2, which is located at the left-hand side of the vehicle, has its 65 inner end 13 bent downward to form an approximately L-shaped arm. The lever is provided with an inner upright portion 14, which is pivoted between its ends at 15 and which has its terminals connected by pivots 70 16 and 17 with the L-shaped arms or ends of the rods 1 and 2, and by this arrangement the rods are reciprocated longitudinally and are not materially oscillated vertically, the length of the stroke or movement necessary to disengage the outer ends of the rods from the coupling-irons not being sufficient to cause 75 any binding of the locking-rods in the guides. The outer portion 17 of the operating-lever is arched at its inner end to clear the L-shaped arm of the right-hand rod 1, and it is adapted to rest upon the same, as illustrated in Fig. 1, when the rods are in engagement with the coupling-irons. The outer end 18 of the operating-lever is bent upward and 80 has an operating-cord 19 or other suitable flexible connection secured to it. The operating-cord 19, which is located at the right-hand side of the vehicle, is designed to extend 85 into the box or body, so as to be within convenient reach of the driver.

It will be seen that the horse-detacher is exceedingly simple and inexpensive in construction, that it is adapted to be readily applied to all kinds of road-vehicles, that it 95 will enable a horse or team to be quickly uncoupled, and at the same time will facilitate changing poles and thills.

What is claimed is—

In a device of the class described, the combination with an axle, of the outer axle-clips 100 having perforated ears, the inner axle-clips provided with guides, the longitudinally-reciprocating locking-rods passing through the

guides and having their outer ends arranged in the perforated ears, said rods being provided with reversely-arranged approximately L-shaped arms extending upward and downward, and the operating-lever consisting of the upright central portion pivoted between its ends and connected above and below the pivotal point with the L-shaped arms, and the outer portion having its inner end arched to clear the adjacent inner end of the adjacent rod and having its outer end bent up-

ward and adapted to be swung upward to withdraw the rods, the weight of the lever operating to hold the rods in their engaging position, substantially as described.

In testimony that I claim the foregoing as my own I have hereto affixed my signature in the presence of two witnesses.

JOHN ROSE.
